(57) **CLAIM**

We claim the ornamental design for an embossed tissue, as shown and described.

DESCRIPTION

FIG. 1 is a plan view of an embossed tissue illustrating the claimed design; and,

FIG. 2 is a fragmentary sectional view of the tissue of FIG. 1 taken along line 2—2 of FIG. 1.

In FIG. 1, the outermost broken lines depict the boundaries of the claimed design; the inner broken lines define one repeat unit of the design. The broken lines form no part of the claim.
